(**) Term: **14 Years**

(21) Appl. No.: **29/317,504**

(22) Filed: **Apr. 30, 2008**

(57) **CLAIM**

The ornamental design for a upper parts unit for an outboard motor, as shown and described.

DESCRIPTION

FIG. 1 is a right side, front perspective view of upper parts unit for an outboard motor showing my new design;

FIG. 2 is a left side, rear perspective view thereof;

FIG. 3 is a right side view thereof;

FIG. 4 is a left side view thereof;

FIG. 5 is a front view thereof;

FIG. 6 is a rear view thereof;

FIG. 7 is a top plan view thereof; and,

FIG. 8 is a bottom view thereof.

The broken line showing of a portion of an upper parts unit for an outboard motor is included for the purpose of illustrating environmental structure and forms no part of the claimed design.
